ATTORNEY

UNITED STATES PATENT OFFICE.

GUSTAVE E. VILLARET, OF LEONIA, NEW JERSEY.

DESIGN FOR A LIGHTING FIXTURE OR ARTICLE OF SIMILAR NATURE.

Application filed August 17, 1927. Serial No. 23,111. Term of patent 7 years.

To all whom it may concern:

Be it known that I, GUSTAVE E. VILLARET, a citizen of the United States, residing at Leonia, in the county of Bergen and State of New Jersey, have invented a new, original, and ornamental Design for a Lighting Fixture or Article of Similar Nature, of which the following is a specification, reference being had to the accompanying drawing, forming a part thereof.

Figure 1 is an elevational view of a lighting fixture showing my new design.

Figure 2 is a fragmentary bottom plan view of the lower ring portion of the lighting fixture shown in Figure 1.

I claim:

The ornamental design for a lighting fixture, or article of similar nature, as shown.
